(57) **CLAIM**

The ornamental design for audio video shelving unit, as shown and described.

DESCRIPTION

FIG. 1 is a front perspective view of a first embodiment of the audio video shelving unit;

FIG. 2 is a front elevational view thereof;

FIG. 3 is a rear elevational view thereof;

FIG. 4 is a top plan view thereof;

FIG. 5 is a right side view thereof (the left side being a mirror image of the right side view);

FIG. 6 is a front perspective view of a second embodiment of the audio video shelving unit; and,

FIG. 7 is a top plan view of the embodiment shown in

FIG. 6 (all other views of the second embodiment having the same appearances as FIGS. 1-5).

The shading on the back support structure of the “audio video shelving unit” is meant to represent “perforations in the surface.”
